UNITED STATES PATENT OFFICE.

JOSEPH SOROKIN, OF DES MOINES, IOWA.

ATTACHMENT FOR MANGLES.

1,178,759.

Specification of Letters Patent. Patented Apr. 11, 1916.

Application filed August 18, 1913. Serial No. 785,219.

To all whom it may concern:

Be it known that I, JOSEPH SOROKIN, a citizen of the United States, residing in Des Moines, county of Polk, and State of Iowa, have invented a new and useful Improvement in Attachments for Mangles, of which the following is a specification.

The object of my invention is to provide automatic means for producing a strong tension on the guide cords, or ribbons, in a mangle used for laundry, and similar purposes.

A further object is to provide such means in a simple, strong, durable and practically inexpensive construction.

My invention consists of certain details of construction hereinafter set forth, pointed out in my claims, and illustrated in the accompanying drawings, in which—

20 Figure I shows a transverse sectional view of a part of a mangle fitted out with my device; Fig. II shows a front elevation view of a mangle fitted out with my device; Figs. III and IV show detail views of one 25 of the spring actuated rods I employ.

Referring to the accompanying drawings the reference numeral 10 is used to indicate the large central roller of a mangle and the numerals 11, 12, 13, 14 and 15, the small 30 rollers thereof. Passing over the small rollers and then under them and between them and the large roller are cords 16, each cord being endless and arranged in the manner shown, which is the ordinary construction. It is necessary to provide means for 35 keeping a tight tension on each of these cords as they are used for guide purposes and soon lose their efficiency on account of stretching and the like. To accomplish this

40 I have mounted a cross bar, 17, to the frame of the mangle so that it will be parallel with the rollers. In said cross bar, properly spaced and arranged to be in line with the guide cords, I have secured upwardly projecting rods 18, adapted for upward and downward movement in their mountings, said rods being held at their upward limit of movement by the coil springs 19, mounted as shown. On the upper extremity of 45 each rod I have mounted a grooved wheel 20.

In practical operation the guide cords pass over the grooved wheels and the tension of the cords is sufficient to hold the spring actuated rod 18, down. As the cords stretch, by reason of use, the spring actuated rods move upward this automatically keeping the required tension on the cords.

Having thus described my invention, what I claim and desire to secure by Letters Patent of the United States is:

1. In combination with the large roller of a mangle, of a series of smaller rollers arranged about the periphery of the large roller, a plurality of endless cords taking over and under the smaller rollers between the latter and the larger roller, and a plurality of independently operable, spring actuated tensioning devices one of the latter for each endless cord to normally maintain the same taut and adapted to yield to permit of the cord flexing whereby any cord may independently give on encountering an irregular surface between it and the large roller and return to its normal position subsequent to the passing of such irregular surface.

2. An attachment for mangles comprising a series of rollers, a plurality of endless cords taking thereover, a cross bar extending between the rollers and within the endless cords and being provided with a plurality of vertical openings therein, a rod having a head and a depending shank extending through each opening of the bar, a spacing sleeve slidably receiving the lower end of each rod and secured in the lower part of each bar opening to space the rod from the walls of the opening, a coiled spring seating on the sleeve and bearing upwardly on the head of the rod, said spring coiling about the rod within the bar opening in the space provided by the spacing sleeve, means securing the rods from dislodgement from the spacing sleeves, and a wheel carried by the head of each rod and engaging with a respective endless cord.

JOSEPH SOROKIN.
